UNITED STATES PATENT OFFICE.

JOHN WILSON AND HENRY HAIN, OF BOSTON, MASSACHUSETTS.

RAILWAY LOCK-SWITCH.

SPECIFICATION forming part of Letters Patent No. 510,750, dated December 12, 1893.

Application filed July 5, 1893. Serial No. 479,634. (No model.)

To all whom it may concern:

Be it known that we, JOHN WILSON and HENRY HAIN, both of Boston, in the county of Suffolk, State of Massachusetts, have invented new and useful Improvements in Railroad-Switches, of which the following is a specification.

In a railroad switch, the essential feature of this invention consists in a horizontal swinging segment or quadrant of a circle, being positioned to present suitable surfaces for a depending arm retained on a car in front of the wheels, to contact such surfaces respectively, in such a manner as to cause such quadrant to swing on its axis, and to both make a clearance for said depending arm, and to actuate suitable levers or rods beneath such quadrant, adapted to ship the switch blade and to automatically release said switch blade before being shipped and to lock said switch blade after being shipped, and the object of this invention is to obviate the necessity of having to employ individual switchmen.

In the drawings forming a part of this application Figure 1, represents a plan view of the invention, and Figs. 2, 3, and 4, are cross sectional views of Fig. 1, taken on or about the line α , α , drawn on said Fig. 1, which said sectional views illustrate the several positions of the switch mechanism.

The switch mechanism case is designed to inclose the switch operating mechanism, as illustrated by the drawings, to protect such from the effects of dirt, &c., and this case as a whole has other features which will presently appear. The top surface of the covering of the case is roughened or can so be as represented by the figure (1), to prevent slipping thereon as is usually done on other surfaces for the same purpose. In the drawings this case cover consists of two sections (2) and (3) bolted by ordinary bolts (4) to the box portion (5). These two sections have their divisional ends respectively overlapping each other as represented by (6) which is to make one set of bolts secure both said ends which are so secured to the cross-piece (7) secured to the box portion as shown by the said drawings.

(8) represents elevated surfaces from the plane of the section covering plate (2) which are so situated as shown by the drawings especially Fig. 1, for to guard the device (A) above the lower plane of said section plate. 55 These raised surfaces are in height sufficient to cause vehicle wheels to mount and pass over the plane of the device (A) above mentioned, in any direction, and such elevations are further designed so as to permit said 60 vehicle wheels to ride over their surfaces with ease by causing their outward sides to the case to incline as shown by the drawings, and these elevated surfaces or parts are still further designed to form passages (9) and 65 (10) with curved entrances which are to permit a depending arm, represented by (11) more fully described later on, to pass through said passages or ways, which have always the device (A) across their way respectively, 70 i. e. alternately, or across either one or the other's path. This device (A) which will be more fully recognized hereinafter is axially engaged with the aforesaid cover portion (2) equal to the center of the width between 75 the outer sides of both passages aforesaid, so as to efficiently swing on such center to respectively cross the path of aforesaid passages which are in width too narrow to permit the wheels of vehicles to enter. The other case 80 covering section (1) is designed so as to complete the junction of two track rails as represented by (12) and also to permit the switching blade (J) to efficiently perform its function. 85

Having now described the features of our switch mechanism containing case the following matter will relate the movable means to actuate the switch blade (J): This depending arm above mentioned, and merely shown 90 in detail in the accompanying drawings as represented by the figures (11), should be situated rigidly in a vertically movable manner at both ends of a car in front of the truck-wheels to enable the manipulator to either 95 cause such depending arm to engage the straight part of the device (A) to operate the switch mechanism, or to permit such arm aforesaid to clearly pass over (not engagedly) the said device, before the first wheels of the 100

car engage the switching point of the track. Further it has not been deemed necessary to illustrate any one application of the means that can be variably designed to act as a 5 shipper on the front of a car to operate the aforesaid device (A) other than the depending portion (11), which, let it be understood represents a stationary or a vertically movable means in detail to cause the said device 10 to swing on its axis to ship the switch blade. This device (A) more properly should be termed a segment or quadrant of a circle which will be hereinafter so termed. (B) represents the vertical shaft to which is rigidly 15 secured the aforesaid quadrant also the arm (C) which has the elongated slot (c) there-through. (13) and (14) are the aforesaid shaft bearings. In the above elongated slot (c) works the vertical stud or pin (D) and to this 20 stud are engaged the horizontal rods or levers (E) and (F). The former is the key lever to this mechanism, and the latter is the switch operating connecting rod. The key rod is engaged with the vertical stud (c) so as to 25 travel or move the complete throw created by the arm (C) through the quadrant (A) while the underneath connecting rod aforesaid is designed to lay a portion of the complete throw aforesaid by having the elongated slots (f) and (f') equal in length 30 engaging the aforesaid stud and the depending stud (e) which is secured to, or is a part of the key lever, of which the object will presently appear. The opposite end of the key lever or 35 rod to that which engages to stud (C) has a Δ shaped head designed to act as operating inclined planes with the locking lever (G) that has corresponding walls (g) to engage such head for such purpose. These Δ shaped 40 walls on the locking lever are located to equal the complete traveling distance of the key rod so that when the key rod has been oppositely moved or the switch been shipped as clearly represented by Figs 2 and 3, the 45 locking lever will be in locking engagement with the connecting rod as illustrated by said views. This locking lever has one end pivotally retained on the vertical uprights (15) as represented by (g'), and the other end, 50 which is the swinging end, depending vertically and of such length as to enter through the openings or holes (f²) on the aforesaid connecting rod, which said holes are in width apart equal to the throw of the switch tongue 55 (J). The above uprights (15) also act as with the uprights (16) to guide the movement of aforesaid levers, and which have also the cross-positions (17) beneath the connecting rod for such to move on but which is optional. 60 (H) represents the switch blade moving lever which is rigidly secured to the switch blade vertical shaft (I) and suitably engaged with the other end of the connecting rod, and to this vertical shaft (I) is secured as shown, 65 the switch blade aforesaid, thus completing the association of parts to this invention.

(18) and (19) represent the aforesaid switch blade shaft's bearings. When the depending arm or rod (11) engages either of the two straight sides of the segment (A) as shown 70 in the drawings it will be seen that such segment or quadrant will be caused to swing on its axis and to first move the key rod sufficient to swing upward the locking lever and by such, effect releasement of the connecting 75 rod as represented by Fig. 4, which said connecting rod is then moved the remainder of the throw to ship the switch tongue which is represented as having been done by Figs. 1, 2, and 3. 80

Having now described our invention, we claim—

1. In a switch, the combination with a suitable switch mechanism case or frame, of a sector or quadrant of a circle secured to a vertical shaft horizontally above the top surface of said case or frame, such shaft having suitable bearings on the case, an arm secured to said vertical shaft, a connecting rod suitably connecting said arm and a switch blade moving lever, such lever being secured to a vertical switch blade shaft, such shaft having suitable bearings on said case or frame, and the switch blade or tongue being secured to said vertical shaft operatively, substantially 95 as described.

2. In a switch, the combination with a suitable switch mechanism case or frame, of a sector or quadrant of a circle secured to a vertical shaft horizontally above the top surface 100 of said case or frame, such shaft having suitable bearings on the case or frame, levers or rods operatively engaging each other, the said case or frame, the aforesaid vertical shaft and a vertical switch blade shaft so as to reciprocally unlock, oppositely ship and lock the switch blade automatically, the switch blade being secured operatively to said vertical shaft, and such shaft having suitable bearings on aforesaid case or frame, substantially 110 as described.

3. In a switch, a switch mechanism case, such having suitable raised surfaces to shield a swinging switch actuating sector, and provided with the switch part of the track, and with suitable lever guide trunnions, 15 and 16 a sector or quadrant of a circle secured to a vertical shaft, said vertical shaft having suitable bearings on aforesaid case, an arm secured to said vertical shaft, said arm having a slot therein, a vertical pin engaging said arm in said slot, a connecting rod connecting said vertical pin and a switch blade moving lever, said connecting rod having suitable slots therein for aforesaid vertical pin and a 125 depending stud to engagedly enter, also suitable holes spaced apart equal to the throw of the switch blade, the switch blade having its other end secured to a vertical switch blade shaft, such shaft having suitable bearings on aforesaid case, and the switch blade being secured to said shaft, substantially as speci- 130

fied, in combination with a rod having one end engaging aforesaid vertical pin, and the opposite end provided with a Λ shaped head, and a depending stud, a locking arm having one end pivotally retained by the case and the opposite end designed to enter the aforesaid connecting rod, and said arm having suitable surfaces to engage the aforesaid Λ

shaped rod head, substantially as and for the purpose described.
